(57) CLAIM

The ornamental design for a snap hair clip, as shown and described.

DESCRIPTION

FIG. 1 is a perspective view of a snap hair clip according to the present design.

FIG. 2 is a right side elevation view thereof.

FIG. 3 is a left side elevation view thereof.

FIG. 4 is a front elevation view thereof.

FIG. 5 is a back elevation view thereof.

FIG. 6 is a top elevation view thereof; and,

FIG. 7 is a bottom elevation view thereof.

The broken lines in the drawings depict portions of the snap hair clip that form no part of the claimed design.

1 Claim, 6 Drawing Sheets
